UNITED STATES PATENT OFFICE.

LLOYD E. CAMERON, OF SOMERVILLE, MASSACHUSETTS, ASSIGNOR TO ALFRED F. MURPHY, OF BOSTON, MASSACHUSETTS.

STAMPING-DIES.

1,400,416.

Specification of Letters Patent. Patented Dec. 13, 1921.

Application filed May 16, 1919. Serial No. 297,645.

To all whom it may concern:

Be it known that I, LLOYD E. CAMERON, a citizen of the United States, and resident of Somerville, county of Middlesex, State of 5 Massachusetts, have invented an Improvement in Stamping-Dies, of which the following description, in connection with the accompanying drawings, is a specification, like characters on the drawings representing 10 like parts in each of the several views.

This invention relates to dies adapted to be removably assembled in stamping presses for producing predetermined forms, such, for example as the numbers on automobile 15 number plates.

These dies consist in a pair of mating die elements, equipped with means to hold them in coöperative relation and normally a small distance apart, so that the sheet or 20 plate material to be stamped may be inserted therebetween, these die pairs being made up as individual units adapted to be assembled side by side on the platen of a press to stamp simultaneously any required 25 series of letters or other forms. The members of these die pairs as heretofore commonly produced have been hinged at one end so as to permit the opening thereof for insertion of the work. This hinge connection 30 has proved objectionable since it does not hold the die members always accurately in mating coöperative relation, particularly after a period of wear, and these dies are often broken from an uneven distribution 35 of strains. The principal object of the present invention is to provide a die pair or couple of the type stated, wherein the die members are mounted and relatively connected for a right line movement toward and from each other, this connection being of a character so that the die members are always held perfectly alined with 40 respect to each other from one end of the dies, leaving the main body portion from 45 the other end of the dies open and free for the insertion of work. The die units in the present invention are further self-contained and since the die members are always in parallelism, when open as well as when 50 closed, they are more convenient for handling, assembling, or storage than in the previously common hinged type of die.

The foregoing and other objects and advantages of the invention will be better understood from the following detailed de-

scription, taken in connection with the accompanying drawings and distinctive features of novelty will then be pointed out in the appended claims.

Referring to the drawings,

Figure 1 is a lengthwise central vertical section, showing a die unit embodying the invention;

Fig. 2 is a lengthwise horizontal section on line 2—2 of Fig. 1;

Fig. 3 is a transverse section on line 3—3 of Fig. 1;

Fig. 4 is a transverse section on line 4—4 of Fig. 2 and showing the die members closed together;

Fig. 5 is a partial elevation showing a series of die units of my invention assembled in a press;

Fig. 6 is a side elevation showing a modified form of die unit with the die members 75 open;

Fig. 7 is a lengthwise horizontal section on line 7—7 of Fig. 6;

Fig. 8 is a fragmentary end view, showing a still further modification;

Fig. 9 is a horizontal section on line 9—9 of Fig. 8;

Fig. 10 is a partial horizontal section corresponding to Fig. 7, showing a further modification; and

Fig. 11 is a fragmentary horizontal section corresponding to Fig. 7, showing a still further modification.

Referring first to Figs. 1 to 4, 10, 11 are mating members of a die unit equipped with the recessed and the projecting outline of the form to be produced, as indicated at 10^a, 11^a respectively. These dies are shown as oblong as required by the outline of the character to be produced in the present illustration. In accordance with my invention, the respective die members are extended at one end some distance beyond the operative portion thereof, i. e. the outline of the character to be stamped, and in this extended portion one of the dies, shown as the die 11, has fixed therein a pair of diagonally spaced apart pins 12, 13. These pins project downwardly from the member 11 and are fitted to slide freely in holes 14 of the lower die 10 which are of a size to closely fit and guide accurately these pins. In the lower die member 10 diagonally spaced apart intermediate the pins 12, 13 are adjustably threaded headed bolts 15, 16, 110

the heads 15^a of these bolts fitting in bores 17 of the upper die, which extend only part way therethrough, so that the bottoms of said bores serve as stop ledges to coöperate with the heads 15^a of the bolts and thus limit the opening movement of the die elements, the extent of this opening movement being regulable by the adjustment of the bolts 15 which may conveniently have kerfs 5 in the heads thereof for this purpose. The portions of the two die members between the pins 12, 13 and the bolts 15, 16 have alining bores 18, 19 therein extending part way therethrough, in which is housed a 10 compression coil spring 20, which normally holds the die members open and apart as far as permitted by the adjustment of the bolts 15, 16. It will be noted that this 15 spring is symmetrically disposed with respect both to the guide pins 12, 13 and with 20 respect to the stop bolts 15, 16, and hence the tendency to binding or cramping of the die members in their relative opening and closing movement is minimized. Thus a die 25 construction is provided wherein the die members are held securely alined and guided for free opening movement with the opening spring disposed for coöperation to best advantage with the guiding and alining 30 members at one end of the die, leaving the entire body portion and other end of the die free and available for the insertion of work thereinto, while the alinement and right line movement of the die members is 35 also insured.

In Figs. 6 and 7 I show a form of the invention wherein die members 21, 22 correspond generally to the die members 10, 11 respectively. In this form, instead of the 40 guide pins 12, 13 I provide on opposite sides at one end of the die members, guide plates or bars 23, 24 respectively, these bars being shown at 25 as fixed to the die member 22 and slidably guided in recessed ways 26 45 provided therefor in the die member 21. It will be noted that these guide bars in this case also are located symmetrically at opposite sides with respect to the coil spring 201 which corresponds to the spring 50 20 of the first described form. In this form the adjustable stop bolts 151, 161 may be arranged and mounted similar to the first described form.

In Figs. 8 and 9 I show a form wherein 55 the die members 27, 28 correspond to the die members 10, 11 with an opening spring 202 similar to and similarly mounted as the spring 20, this form also having adjustable bolts 152, 162. In this form the 60 means for holding the die members rela-

tively guided and alined consists in a bar 29 which may be fixed to the upper die member, as indicated at 30 and projects downward with a dove-tailed sliding engagement as seen at 29' in the lower die 65 member 27.

In Fig. 10 I show a form similar to Figs. 6 and 7, except that the guide bars 23^a, 24^a have a dove-tailed sliding fit in the lower die member adapted to effect a more accurate guiding relation between the die members. The form shown in Fig. 11, similar to that of Figs. 8 and 9 except that the bar 29^a corresponding to the bar 29 is rabbed at its sides, as seen at 290 and has 70 a slidable fit in a correspondingly shaped recess in the lower die. I am aware that the invention may be embodied in other specific forms without departing from the spirit or essential attributes thereof and I therefore desire the present embodiment to be considered in all respects as illustrative and not restrictive, reference being had to the appended claims rather than to the foregoing description to indicate the scope of the 80 invention.

Having described my invention, what I claim as new and desire to secure by Letters Patent is:

1. A self-contained die unit adapted for 90 removable assemblage in a stamping press, comprising a pair of oblong die blocks having mating faces bearing the die impression to be produced and adapted to be opened to permit insertion of work there- 95 between from one end to a point adjacent the opposite end, said blocks equipped with spring means to hold them normally apart, and with means for holding them alined with respect to each other located at, and 100 limited to, the end portions thereof opposite the end from which the work is inserted.

2. A self-contained die unit adapted for 105 removable assemblage in a stamping press side by side with other similar units and comprising a pair of die blocks bearing on mating faces thereof the die impression to be produced and adapted to receive work therebetween from one end thereof, the 110 other ends thereof equipped with alining means, and with spring means normally holding them apart, such means being limited to the extreme end portion of the blocks whereby the major portion thereof is left 115 free for the insertion of work.

In testimony whereof, I have signed my name to this specification.

LLOYD E. CAMERON.
